LEWIS CRAVEN ORD, OF MONTREAL, QUEBEC, CANADA, ASSIGNOR TO CANADIAN GOLD CAR HEATING & LIGHTING COMPANY, LIMITED, OF MONTREAL, CANADA, A CORPORATION OF CANADA.

MEANS FOR REGULATING STEAM-HEATING SYSTEMS.

1,076,444.

Specification of Letters Patent.

Patented Oct. 21, 1913.

Application filed November 11, 1911. Serial No. 659,847.

To all whom it may concern:

Be it known that I, LEWIS CRAVEN ORD, of the city of Montreal, Province of Quebec, Canada, have invented certain new and useful Improvements in Means for Regulating Steam-Heating Systems; and I do hereby declare that the following is a full, clear, and exact description of the same.

This invention relates more particularly to controlling devices adapted to regulate the heating capacity of a steam radiator by controlling the escape of the water of condensation therefrom and it has for an object to provide an improved form of controller which will be simple in construction and of comparatively small expense to manufacture.

Another object is to provide a construction for a controller which will permit of the flow of steam therethrough being shut off at desired times and the full flow of steam sent through the radiator.

For further comprehension of the invention and of the objects and advantages there- 25 of reference will be had to the following description and appended claims, and to the accompanying drawings forming a part of this specification in which similar reference characters indicate the same parts and 30 wherein—

Figure 1 is a side elevation of a railway car heater having my invention applied thereto; Fig. 2 is a plan view thereof; Fig. 3 is a detail vertical sectional view of my improved regulator; Figs. 4, 5 and 6 are horizontal sectional views taken respectively on the lines 4 4, 5 5 and 6 6 of Fig. 3 and looking in the directions indicated by the arrows, Fig. 5 being on a slightly 40 larger scale than Figs. 4 and 6; and Fig. 7 is a detail face view of the indicator plate.

In the drawings my invention is illustrated applied to the heating of a water system, such for instance as is suitable for 45 car heating, a steam radiator being indicated at A while a water jacket for containing the water to be heated is shown at B and the flow and return pipes of the hot water system at C and D respectively; these 50 parts being of any approved construction, it being understood of course, that the application of my invention is not limited to a radiator employed for the particular purpose here indicated.

My improved regulator comprises a stand 55 pipe 2, screwed at its lower end into a casting 3 forming a valve casing the lower end of which is bored and tapped to receive a plug 4 having a central passage 5 leading therethrough from top to bottom, the upper 60 end of the passage being outwardly flared as at 6 to form a valve seat, the lower end of the passage being enlarged and tapped to receive the upper end of the usual waste pipe 8 which is screwed therein, the waste 65 pipe leading to a thermostatic trap 7 of usual construction and to which detail reference does not need to be made. The side wall of the valve casing has a tapped opening or port 9 into which is screwed the 70 end of the pipe 10 leading from the lower end of the radiator, the upper end of the stand pipe being screwed into a head 11 which has in its side wall a tapped opening or port 12 into which is screwed the end of 75 a branch steam pipe 13 leading from the main steam supply pipe 14 which connects to the upper end of the radiator in the usual manner, the pipe 14 being here shown as provided with a valve 13' located at a 80 point between the branch pipe 13 and the radiator.

Located centrally within the stand pipe and extending from top to bottom thereof is a tube composed of a number of sections, 85 there being three of these sections 15, 16 and 17 respectively here shown, this tube controlling the communication between the port 9 and the outlet passage 5 to the waste pipe by adjustment of the tube as a whole 90 and of the sections relatively to one another. As here shown these sections have screwed on the lower ends thereof sleeves 20, 21 and 22 respectively, whose bottom faces are bevelled to form valves 20', 21' and 22', the 95 valve 22' on the lower section being adapted to seat at times upon the before mentioned seat 6, while the valves 20' and 21' are adapted to seat at times on seats 16' and 17' formed on the adjacent upper ends of 100 the sections 16 and 17. These sections are connected to one another in a manner to permit both of limited relative movement therof and of the whole tube being raised or lowered in the stand pipe to open or close 105 the valves 20', 21' and 22' and so vary the level at which the water of condensation may escape from the stand pipe to the

outlet passage 5 as will be presently pointed out. As here shown these sections are connected one to another by coupling rings 24 and 25 screwed upon the lower ends of the sleeves 20 and 21 and having inturned annular flanges 24' and 25' engaging under circumferential flanges on the tops of the sections 16 and 17 and loosely encircling such sections, these coupling rings being of sufficient length to allow of movement of the valves 20' and 21' the coupling rings being formed with openings or parts 26 and 27 respectively communicating with the spaces between such valves and seats when the valves are open while the section 15 is provided with openings or ports 28 near its upper end. The sectional tube is centered within the stand pipe by means of circumferential flanges 29 cast on the sleeves 20, 21 and 22 and provided with vertical ports 30 to permit of the passage of the water of condensation or steam.

Screwed upon the upper end of the section 15 is a cap 32 whose top is formed to present a valve 33 adapted to register with a downwardly facing seat 34 on a ring 35 screwed into the top of the stand pipe, this valve controlling admission of the steam from the branch pipe 13 to the stand pipe as will be readily seen by referring to Fig. 3.

Formed integrally with the cap 32 and extending upwardly therefrom is a stem 37 which projects through a plug 38 screwed into the top of the head 11, there being a screw thread connection 39 between the stem and plug so as to cause rotation of the stem to move it vertically, a packing gland 40 preventing escape of the steam. The pitch of the thread 39 is preferably such as to cause the stem to move vertically at each complete revolution, a distance equal to the amount of lost motion between each of the sections. Mounted upon the upper end of the stem is a handle 41 having a downturned indicating finger or pointer 42 adapted to register with different ones (according to the height of water to be maintained) of a series of indentations 43, or other suitable marks, on a segmental plate 44 secured as by screws 45 to the head 11. These indentations may be designated Full, $\frac{3}{4}$, $\frac{1}{2}$ and $\frac{1}{4}$ and show, according to which one the pointer registers with, whether the controlling tube is adjusted to cause the water of condensation to escape directly to the waste pipe under valve 22', or through respective ones of the openings 26, 27, 28.

Operation: If only a small portion of the heating surface of the radiator is to be utilized the handle 41 is turned until the indicator points to $\frac{1}{4}$ in which position the valves 20', 21' and 22' will all be seated upon the respective seats, closing all communication between the stand pipe and out-

let passage except through the openings in the top section and consequently causing the water of condensation to rise in the stand pipe (and likewise in the radiator) to the level of such openings, thus reducing the effective heating surface of the radiator to that above such level, the water flowing from the stand pipe through such openings and down the tube whose bottom is in communication with the outlet passage 5. To further increase the heating capacity of the radiator the handle is turned until the indicator points to $\frac{1}{2}$ in which position the valve 20' will be lifted from its seat by reason of the loose connection between the sections of the tube and the water of condensation will escape through the openings 26, the valves 21' and 22' being still held closed by the weight of the sections 16 and 17, while a further movement of the handle will cause the section 16 to be lifted and the valve 21' to be raised and the water of condensation to escape through the openings 27. Any slight leakage that may take place through the valves due to the fact of the valves being held in place only by the weight of the tube sections will not be sufficient to affect the proper working of the device because of the continuous supply of the water of condensation from the radiator, while it will be obvious that with the water of condensation at the highest level the handle can be turned to force the sections firmly down upon one another and tightly close the valves. To cause the full heating surface of the radiator to be utilized the handle is turned farther until the indicator points to Full, in which position the valve 22' is lifted from its seat, (the whole tube being suspended in the stand pipe) and the water of condensation flows directly to the waste pipe, the valve 33 preferably seating on its seat and shutting off the steam from the controller when the full heating surface of the radiator is being utilized.

The construction permitting the steam being shut off from the regulator when the full heating surface of the radiator is to be utilized has been found to be very desirable because of the liability to a more rapid condensation of the steam in the radiator than in the controller resulting in a higher pressure in the controller than in the radiator with a consequent tendency of the back pressure from the controller through the pipe 10 to prevent the escape of the water of condensation and cause it to back up in the radiator.

To prevent any chance of the radiator freezing in very cold weather the handle of valve 13' may be removed (with the valve open) thus rendering it impossible to completely shut off the radiator as the portion thereof above the openings 28 will always be open to the steam supply. In milder weather the valve handle can be replaced

and the steam supply to the radiator shut off, while at the same time a passage to the steam trap through the regulator will be left open thus protecting the thermostatic trap from freezing, to which it might be liable because of its exposed position.

I claim:

1. In combination, a steam radiator, a steam supply device, a stand pipe connected to the radiator to have the water of condensation escape therethrough, means connecting the stand pipe to the steam supply device, means whereby such stand pipe may be cut off from such steam supply device, means operable automatically by said last named means to permit the water of condensation to escape at a certain predetermined level when said stand pipe is cut off from the steam supply device, and means connecting the radiator to the steam supply independently of the stand pipe.

2. A steam radiator regulator comprising a stand pipe having a drip port, and an inlet port adapted to receive water of condensation from a radiator, a tube within the stand pipe adapted to control the escape of water of condensation therefrom, such tube comprising a series of vertically and relatively adjustable members arranged to provide passages between the ends thereof for the flow of water from the stand pipe at different levels, and means whereby such members may be adjusted relatively to each other to govern the passage therebetween.

3. A steam radiator regulator comprising a stand pipe having a drip port, and an inlet port adapted to receive water of condensation from a radiator, a tube within the stand pipe adapted to control the escape of water of condensation therefrom, such tube comprising a series of vertically and relatively adjustable members arranged to provide passages between the ends thereof for the flow of water from the stand pipe at different levels, and means whereby such members may be adjusted relatively to each other to govern the passage therebetween the bottom one of such tubes carrying a valve adapted to control the passage of the water of condensation from the stand pipe exterior to the said tube.

4. A steam radiator regulator comprising a stand pipe having a drip port and an inlet port adapted to receive water of condensation from a radiator, means connecting the stand pipe to the steam supply, means within the stand pipe for regulating the level at which the water of condensation escapes, and means actuated by a common device with the last mentioned means for cutting off the steam supply to the stand pipe when the water of condensation is escaping at a certain predetermined level.

5. In a steam radiator regulator, a tube open at its lower end and made up of a

series of relatively adjustable sections having their adjacent ends formed to present valves and valve seats respectively, means whereby the said sections may be adjusted relatively to one another to move the valves toward or away from the said seats, and means to support the tube.

6. The combination with a steam radiator, a stand pipe in communication with the radiator to receive water of condensation therefrom and having a drip port, a tube within the stand pipe to control the escape of water from the radiator through the stand pipe and movable to have its lower end placed in direct communication with the drip port and made up of a series of relatively movable sections arranged to provide passages therebetween for the flow of water from the stand pipe at different levels, means whereby such sections may be adjusted toward and away from one another and whereby the whole tube may be adjusted within the standpipe to govern the passage of the water of condensation from the inlet to the drip port of the stand pipe.

7. A steam radiator regulator comprising a stand pipe having a drip port and an inlet port adapted to receive water of condensation from a radiator, such stand pipe also having at its upper end an inlet port in communication with a source of steam supply, a tube within the stand pipe movable to have its lower end placed in direct communication with the drip port and having above its lower end an opening forming a passage between the tube and the stand pipe, such tube being provided with valves at its lower and upper ends, and means for adjusting such tube vertically to cause the said valves to alternately open and close the said drip port and the port in communication with the steam supply respectively as the tube is moved in opposite directions.

8. In a steam radiator regulator, a tube open at its lower end and made up of a series of relatively adjustable sections having their adjacent ends formed to present valves and valve seats respectively, means whereby the said sections may be adjusted relatively to one another to cause the valves to be lifted from or closed upon the said seats in succession, and means to support the tube.

9. A steam radiator regulator comprising a stand pipe adapted to have the water of condensation escape therethrough, such stand pipe having a bottom member provided with an outlet opening, a tube within the stand pipe comprising a series of sections adjustable toward and away from one another to provide passages therebetween for the flow of water from the stand pipe the upper end whereof is formed with an inlet opening, means whereby such tube may be seated upon such bottom member with its lower end registering with the said outlet

opening and the passages between the sections closed or the sections successively lifted from one another and the whole tube lifted from such bottom member.

5 10. In a steam radiator regulator, a stand pipe having an outlet, a tube in the stand pipe having its interior in communication with said outlet and made up of a series of relatively movable sections having adjacent 10 lower and upper ends formed to present respectively valves and valve seats, and means connecting the sections together to permit of limited relative movement thereof and bodily movement of the tube in unison, such 15 means permitting of the passage of the water of condensation between the said adjacent ends.

11. A steam radiator regulator comprising in combination, a stand pipe adapted 20 to have the water of condensation escape therethrough, such stand pipe having a bottom member formed to present a discharge opening, a tube extending within the stand pipe leading from top to bottom thereof, 25 the lower end of such tube presenting a valve adapted to control the said opening

and cause at times escape of the water of condensation to be through such tube, such tube being made up of a plurality of sections the adjacent lower and upper ends of which are formed to present respectively valves 30 and seats, coupling devices connecting the sections together to permit of limited movement of the valves with respect to the seats, such coupling devices presenting openings 35 adapted to permit of flow of the water of condensation from the stand pipe to the tube when the valves are raised, a stem leading upwardly from the said tube, means for adjusting such stem vertically to cause different ones of the before mentioned valves to be lifted from their seats to vary the level at which the water of condensation may escape from the stand pipe to the said outlet 40 opening.

45 In testimony whereof, I have signed my name to this specification, in the presence of two subscribing witnesses.
